E. A. GODFREY.
DEVICE FOR HOLDING METAL HANDLES OF CUTLERY WHILE BEING
SOLDERED.

No. 28,714.

Patented June 12, 1860.

UNITED STATES PATENT OFFICE.

EDWARD A. GODFREY, OF HARTFORD, CONNECTICUT, ASSIGNOR TO ROGERS,
SMITH & CO., OF SAME PLACE.

IMPROVEMENT IN SOLDERING HANDLES OF CUTLERY.

Specification forming part of Letters Patent No. 28,714, dated June 12, 1860.

To all whom it may concern:

Be it known that I, EDWARD A. GODFREY, of Hartford, in the county of Hartford and State of Connecticut, have invented a new and useful Device for Holding, while being Soldered, Metal Handles for Cutlery; and I do hereby declare that the following is a full, clear, and exact description of the same, reference being had to the annexed drawings, making a part of this specification, in which—

Figure 1 is a front elevation of my invention; Fig. 2, a side elevation of the same partially bisected; Fig. 3, a plan or top view of the same; Fig. 4, an outline of a handle having its parts secured together by wires, as heretofore.

Similar letters of reference indicate corresponding parts in the several figures.

The object of this invention is to facilitate the securing together of the two longitudinal parts of metal handles for cutlery so that said parts may be readily clamped and at the same time held together for the purpose of being united by soldering.

To enable those skilled in the art to make and use my invention, I will proceed to describe its construction and necessary manipulation required in applying the handles to the device.

A represents a bar or support, in the upper end of which a vertical rod, B, is fitted, and on this rod a socket, C, is placed and allowed to turn freely.

On the socket C a horizontal plate, D, is placed, said plate having two uprights, E E, attached to it, in the upper ends of which horizontal rods F F are fitted and secured by set-screws *a a*.

To the plate D two uprights, *b b*, are attached. These uprights *b* are in line with the uprights E E, and on each upright *b* a tube, G, is fitted and allowed to slide freely up and down.

To the upper ends of the tubes G a plate, H, is attached, said plate having a piece of pumice-stone, I, secured to it.

On each tube G a spiral spring, J, is placed, the lower ends of said spring bearing on the plate D, and the upper ends bearing against the under side of the plate H. The springs

J have a tendency to keep the plate H upward toward the rods F F.

To the under side of the plate D a rod, K, is attached. This rod extends down nearly to the flooring, and has a treadle connected to its lower end. The plate H has two curved rods, *c c*, attached to it, one near each end of the pumice-stone. These curved rods *c c* form bearings for the handle L, and these bearings are in line with the rods F F, as shown clearly in Fig. 1. The handle L is formed of two longitudinal parts, which are swaged or struck up in proper form, as usual. The edges of the two longitudinal parts of the handle are rubbed with moistened borax, fitted together, and then placed on the bearings *c c* and on the pumice-stone I, the plate H being depressed by pressing down the treadle in order that the handle may be placed below the rods F F. When the treadle is relieved from the pressure of the foot the springs J J force the plate H up, and the handle L is pressed snugly against the rods F F, and the two parts of the handle are thereby retained in proper position, and also secured on or over the pumice-stone. When the handle L is thus secured on or over the pumice-stone, the operator, by means of a blow-pipe flame and a stick of solder, solders the two parts of the handle together, the socket C being turned on the rod B, so as to bring all parts of the joint of the handle under the action of the flame. The pumice-stone being a non-conductor of heat of course favors the soldering operation. This, however, is well known, and is commonly used for such purposes. By this arrangement the two longitudinal parts of the handle are connected together, and the handle secured to the pumice-stone by a very simple adjustment of the plate H, and the time and trouble of wiring the parts of the handle together for soldering, as shown in Fig. 4, and, as hitherto practiced, is avoided, and a considerable saving effected both as regards labor and the stock employed for solder, for in the original way of soldering the solder was rasped fine and a quantity poured into the handle, and the portion which adhered to the moistened borax was fused by the heat at the outer side of the handle, all the rest being use-

less. By employing the stick of solder at the outer side of the handle a great saving in the stock of solder is not only effected, but the work is greatly expedited.

Having thus described my invention, what I claim as new, and desire to secure by Letters Patent, is—

The rods A A, attached at one end to the

cap B, and having a plate, D, springs F F, and nuts E E fitted on them, substantially as and for the purpose set forth.

EDWARD A. GODFREY.
